UNITED STATES PATENT OFFICE.

WILLIAM RICHARD WHITE, OF BLOOMINGTON, ILLINOIS.

SWINGING GATE.

SPECIFICATION forming part of Letters Patent No. 651,686, dated June 12, 1900.

Application filed February 13, 1900. Serial No. 5,077. (No model.)

To all whom it may concern:

Be it known that I, WILLIAM RICHARD WHITE, a citizen of the United States, residing at Bloomington, in the county of McLean and State of Illinois, have invented certain new and useful Improvements in Swinging Gates, of which the following is a specification.

This invention relates to swinging gates adapted to be operated by levers pivoted to move in a vertical plane, and particularly to devices for preventing lateral play of such levers when operated to move the gate.

The invention will be fully described in the following specification, reference being had to the accompanying drawings, in which—

Figure 1 is a perspective view of a swinging gate embodying my present invention. Fig. 2 is a bottom plan view of part of the operating-lever, showing one form of the swinging guide or the rod connected to said lever and to a fixed support, the latter being in section. Figs. 3, 4, 5, and 6 are similar views showing other forms in which my invention may be embodied.

I will first describe briefly such parts of the apparatus as are necessary to understand its operation.

The gate 10 is provided with a sliding latch-bar 11, connected to a spring-latch 12, and is hinged at one end to a post 13 in such manner that it can swing against either of the posts 14 or 15, each of which posts is provided with a catch 16, with which the latch engages.

The operating hand-levers for the gate are indicated by 20, one being pivoted intermediate its ends to a post 21, adjacent to the post 15, and the other to a block 22, extending diagonally from the post 13. A tie-bar 24 is fastened to the upper ends of the posts 21, 15, and 13 and also to the upper end of the block 22, and this, together with the brace 25, insures a firm pivotal support for the levers 20. The opposing ends of the levers 20 are loosely connected by means of a pin 27, firmly secured to one of said levers and extending loosely between two cross-pin 28 in the other lever. By pulling on either lever at its outer end the opposing ends, which normally sag downward, will be lifted.

To transmit movement from the levers to the gate, I employ an arm indicated gener-

ally by B and consisting of a metal bar or rod formed with an eye b at its upper portion and bent into the form of a crank-handle c at 55 its lower portion. It is also provided with a lateral extension d, and the latter is bent to form a journal e, which lies substantially parallel to the middle portion of the arm and which has a bearing in an opening formed in 60 the top rail of the gate and forms a pivot about which the arm may turn. The crank-handle portion engages oppositely-extending loops or eyes 17 and 18, formed, respectively, in the latch-bar 11 and the bar immediately 65 above it, and when the arm B turns on its pivot the loop 18 acts as a fulcrum upon which the crank rocks, and the latch-bar is thus moved longitudinally to operate the latch. A link 29 is pivotally connected at 70 one end to the eye b and at its other end to an eye 30, secured to one of the levers.

The construction so far described forms no part of my present invention; but I may state that the latch-bar-operating devices when 75 constructed as above described depend for successful operation on preventing the lever to which the link 29 is connected from having any noteworthy lateral movement at its inner end, and the object of my present invention is to insure against such movement, while at the same time offering no resistance to the vertical movement of the lever. To carry out my object, I make use of a swinging guide or tie-rod pivotally connected to 80 the lever and to a fixed support in such manner that the lever can have practically no lateral movement, but is entirely free to move vertically within the limits necessary to operate the latch-bar and the gate. My invention 85 may be embodied in several forms, and in the drawings I have illustrated several forms.

In Fig. 2 the tie-rod 40 is bent at each end to form arms 41 and 42, extending in opposite directions, the former being at substantially a right angle to the rod and the other at an obtuse angle. In applying this tie-rod an eyebolt 43 will be secured in the lever 20 to receive the arm 41, so that it will 95 lie longitudinally parallel with the lever, and the arm 42 will fit loosely in an opening in the post 13 and lie substantially parallel with the lever 20. The reason for bending the arm 100

42 at an obtuse angle is to bring the connection between the arm 41 and the lever 20 nearer the inner end of the lever, and therefore farther away from the pivot of the lever.

5 It is obvious, however, that both arms may be bent at a right angle; but of course the tie-rod 40 would in such case be a little shorter. It is obvious that as the lever swings vertically the arm 42 will turn in its bearing and to there will be a little sliding movement between the arm 41 and the eyebolt 43; but the lever 20 will not and cannot have lateral movement to any appreciable extent.

Instead of bending one end of the rod 40 15 to form the arm 42 it may be bent into the form of an eye 44 to be engaged in the eye 45 of an eyebolt secured in the post 13, as shown in Fig. 3. Also, as shown in Fig. 4, the ends of the rod 40 may both be bent to form eyes 20 46 to be engaged in the eyes of eyebolts secured in the lever 20 and post 13, respectively. Another form is shown in Fig. 5, in which a bar 47 is secured to the post 13 and projects 25 outwardly therefrom away from the lever 20 and is provided at its outer end with a horizontally-disposed opening 48. In this case one end of the rod 40 is bent to form a hook 49, which engages in the opening 48, while its other end is bent to form an eye 51, engaging in the eye of an eyebolt 52 in the lever 20. Another form is shown in Fig. 6, in which one end of the rod is bent to form an arm 42, which is journaled loosely in the post 13, and its other end is bent into the form of 30 an eye 53, engaging in the eye of an eyebolt 54 in the lever 20.

In each case illustrated the connection of the tie-rod to the lever is at a point between the pivot and the inner end of the lever and 40 much nearer to the former than to the latter, and the vertical swing of the tie-rod is much less than the similar movement of the end of the lever.

All the different forms of swinging guide 45 or tie-rod described operate in substantially the same manner to prevent any appreciable lateral movement of the lever 20, while leav-

ing it perfectly free to move vertically within the necessary limits.

If preferred, similar guides or tie-rods may 50 be connected to the other lever 20 and to the post 13; but while this may be desirable for more fully insuring the true vertical movement of the levers it is not necessary, and one guide or tie-rod will be sufficient for each 55 gate; provided it be connected to the lever to which the link 29 is connected, and which lever is in all cases the one which transmits movement to the latch-bar.

Having described the invention, I claim— 60

1. In a swinging gate of the general class described, the combination with the operating-lever pivotally supported between its ends to swing in a vertical plane, of a swinging guide or tie-rod loosely connected at one 65 end to the lever at a point near the pivot of the latter, and at the other end to a fixed support, substantially as and for the purposes set forth.

2. In a swinging gate of the general class 70 described, the combination with the operating-lever, of a swinging guide or tie-rod having one end bent to form an arm, an eyebolt on the lever through the eye of which the arm passes loosely, and a fixed support to which 75 the other end of the rod is loosely connected, for the purpose set forth.

3. In a swinging gate of the general class described, the combination with the operating-lever, of a tie-rod having its ends bent to 80 form arms extending in opposite directions, one of said arms being at substantially a right angle to the rod and the other at an obtuse angle thereto, an eyebolt in the lever through the eye of which the right-angled arm extends, and a fixed support in which the other arm is journaled, for the purpose set forth.

In testimony whereof I have signed my name to this specification in the presence of two subscribing witnesses.

WILLIAM RICHARD WHITE.
